METHOD FOR USE IN MANUFACTURING
SHOES

Fred S. Sherman, Somerville, Mass., assignor to
United Shoe Machinery Corporation, Borough
of Flemington, N. J., a corporation of New
Jersey

Application December 28, 1937, Serial No. 182,103

9 Claims. (Cl. 12—145)

This invention relates to a method for use in the manufacture of shoes in which the edges of the lacing opening are held in proper position during the lasting operation by a piece of flexible material attached to the lacing portions of the upper, to the piece of material and to an upper provided with the piece and ready to be mounted on a last.

In the manufacture of laced shoes it has been customary to provide reinforcements or stays between the lining and the upper along each edge of the lacing opening, to punch lacing holes through the three layers and, if desired, to insert eyelets which extend through the lining and the stays and may or may not extend through the lacing holes in the upper, after which the upper is laced with a cord in such manner that when it is placed on a last the edges of the lacing opening are held in proper position during the lasting operation, the cord being cut or otherwise removed when the shoe is to be pulled from the last.

The purpose of the present invention is to dispense with this temporary lacing by attaching the lacing portions of the upper together in proper relation by means of a piece of fabric or other suitable material, said piece being preferably of such shape and so located that, after it has served the purpose of holding the lacing portions in position during the lasting and subsequent operations and that part of which bridges the lacing opening has been cut away, the part or parts which remain in the shoe serve as stays in the localities of the lacing holes.

35 Referring to the accompanying drawing,

Fig. 1 is a perspective of a piece of flexible sheet material which is to be attached to a shoe;

Fig. 2 is a perspective of a lasted Bal shoe the lacing portions of the quarter of which are attached together by the piece of sheet material, said piece being in process of being slit to permit the shoe to be removed from the last;

Fig. 3 is a vertical cross section of a portion of the lasted shoe of Fig. 2 on the line III—III 45 of that figure;

Fig. 4 is a perspective of a portion of the shoe after its removal from the last, that part of the piece of flexible material which bridges the lacing opening being in process of being cut away; 50 and

Fig. 5 is a perspective of the piece of flexible material folded into a convenient shape for attaching it to an upper.

The piece of flexible sheet material 5, which 55 provides two stays, one for each lacing portion

of the quarter, in the locality of the lacing holes 7, may be of any suitable strong material, such as "Tufsta." It is preferably of truncated wedge shape and is provided near its narrower end with a cross-mark which conveniently may be a cross-slit 9. Starting from a point on the slit is a crease 11 which extends substantially medially of the piece and parallel to its long axis to the wider end of the piece, such crease facilitating the bending of the piece along its longitudinal middle about the ridge of the instep of a last. The piece is also provided with two creases or marks 13 which start from the cross-mark 9 and diverge toward the wider end of the piece, said creases or marks 13 being substantially parallel respectively to the diverging edges of the piece. When the piece is being attached to the lacing portions of the quarter 14, the cross-mark 9 is located at or near the base of the V-shaped lacing opening close to or in register with the vamp seam 16 20 and the marks or creases 13 provide means for locating the piece properly with respect to the edges of the opening. These marks or creases, it will be understood, are not essential but contribute greatly to the proper locating of the piece 25 in the upper of the shoe. The piece is fastened to the lacing portions of the quarter and to the lining, if there is a lining, preferably by rows of stitches 15, and the piece extends far enough beneath each lacing portion of the quarter to serve 30 as a stay in the locality of the lacing holes. Before the piece 5 is stitched in place it is preferably folded into the shape shown in Fig. 5 so that first one edge of the lacing opening may conveniently be brought into register with one crease 13 and 35 stitched, and then the other edge may be brought into register with the other crease 13 and stitched.

The lacing holes 7 are now punched and eyelets—if they are to be provided—are inserted. 40 In the illustrated shoe, the quarter of which has a lining 17, blind eyelets 18 are used which pass through the lining and the piece 5 but not through the quarter 14. A tongue, which may be of leather 21 having a fleece lining 23, is attached 45 by the seam 24, and the upper is mounted upon a last 25 and lasted. The piece 5 withstands the strains of the lasting operation and maintains the edges of the lacing opening in proper position. Further manufacturing operations, such 50 as attaching the sole, are then performed. When the shoe reaches the stage at which it is to be removed from the last, a cut is made in the piece 5, for example by slitting it with a knife 27, as indicated in Fig. 2. Thereafter, and commonly 55

when the shoe is otherwise finished, the piece 5 is trimmed, for example with the knife 27, as indicated in Fig. 4, by two cuts parallel respectively to the edges of the lacing opening of the 5 quarter so as to remove all of the piece 5 which bridges the opening, the trimming being done by undercuts so that the edges of the piece 5 and of the lining 17 are not exposed to view in the finished shoe.

10 When this has been done, the piece 5 consists of two arms extending along the edges of the lacing opening, said arms taking the place of the two usual eyelet stays. In the illustrated construction, in which a Bal shoe is shown, the two 15 stays are arms of a V, since the piece 5 extends across the line of stitches 16 by which the vamp 31 is attached to the quarter; but whether they are arms of a V or separate pieces will depend upon the style of the shoe and upon how the 20 piece 5 is located. In a shoe of the Blucher type, for example, the stays would be separate pieces. It should also be noted that a piece corresponding to the piece 5 for use with a Blucher shoe need not be of truncated shape, need not have the 25 cross-mark 8, and that the marks corresponding to the marks 13 need not approach each other at the lower end of the piece.

Having thus described my invention, what I 30 claim as new and desire to secure by Letters Patent of the United States is:

1. The method of providing stays on the lacing portions of the upper of a shoe and a means for holding the portions in proper position during the lasting operation which comprises attaching 35 the portions together by a piece of flexible sheet material which bridges the space between the edges of the lacing portions and extends beneath each portion far enough to serve as a stay, and subsequently removing only that part of the piece 40 which bridges said space, leaving the remainder to serve as stays.

2. The method of providing stays on the lacing portions of the upper of a shoe and a means for holding the portions in proper position during 45 the lasting operation which comprises attaching the portions together by a piece of flexible sheet material of generally truncated wedge form which extends beneath each portion far enough to serve as a stay, and subsequently removing only that part of the piece which extends between the edges of the lacing portions, leaving the remainder of the piece to serve as stays.

3. The method of providing stays on the lacing portions of the upper of a lined shoe and a means 55 for holding the portions in proper position during the lasting operation which comprises stitching to the portions a piece of flexible sheet material which bridges the lacing opening, punching holes through the upper, the lining and the piece, and subsequently removing only that part of the 60 piece which bridges the opening, leaving the remainder of the piece to serve as stays.

4. The method which comprises attaching the lacing portions of the upper of a shoe together

by a piece of flexible sheet material strong enough to withstand the strains of the lasting operation, said piece extending far enough beneath each portion to serve as a stay in the localities of the lacing holes, performing subsequent operations including punching lacing holes, mounting the upper on a last and lasting it, and subsequently removing a part of the piece which bridges the lacing opening.

5. The method which comprises attaching the lacing portions of the upper of a shoe together by a piece of flexible sheet material strong enough to withstand the strains of the lasting operation, said piece extending far enough beneath each portion to serve as an eyelet stay, performing 15 subsequent operations including inserting eyelets, mounting the upper upon a last and lasting it, and subsequently removing a part of the piece which bridges the lacing opening.

6. The method which comprises attaching the lacing portions of the upper of a shoe together by a piece of flexible sheet material strong enough to withstand the strains of the lasting operation, said piece extending far enough beneath each portion to serve as an eyelet stay, performing 25 subsequent operations including inserting eyelets, mounting the upper upon a last and lasting it, slitting the piece to permit removal of the last, and trimming off those parts of the piece which extend out beyond the edges of the lacing 30 opening.

7. A lined upper ready to be mounted upon a last, the lacing portions of the upper being attached together by a piece of flexible material having lacing holes passing through it, said piece 35 being adapted when the upper has been mounted on the last to hold the portions in proper position during the lasting operation, parts of said piece lying between the lacing portions and their linings in position to serve as stays in the localities 40 of the lacing holes.

8. A piece of strong flexible material adapted to be attached to the lacing portions of the upper of a shoe and to hold said portions in position during the lasting operation, parts of said 45 piece being adapted to serve as eyelet stays, said piece being of truncated form, having a mark extending crosswise adjacent to its narrower end, and being provided with three creases one extending from the cross-mark parallel to the axis 50 of the wedge-shaped piece and two others which start at the cross-mark and diverge toward the wider end of the piece.

9. A piece of strong flexible material adapted to be attached to the lacing portions of the upper of a shoe and to hold said portions in position during the lasting operation, parts of said piece being adapted to serve as eyelet stays, said piece being of truncated wedge form, having a mark extending crosswise adjacent to its narrower end, and being provided with two creases which start at the cross-mark and diverge toward the wider 60 end of the piece.

FRED S. SHERMAN.
